UNITED STATES PATENT OFFICE.

JAMES H. GEORGE, OF NEW YORK, N. Y.

BARREL FASTENING.

Application filed May 20, 1919. Serial No. 298,412.

To all whom it may concern:

Be it known that I, JAMES H. GEORGE, a citizen of the United States, and a resident of the borough of Manhattan, city, county, and State of New York, have invented a certain new and useful Improvement in Barrel Fastenings, of which the following is a specification.

My invention relates to means for securing the staves of a bilge barrel together in such a manner that the securing means or hoops may be readily removed from the barrel in order that the same may be knocked down and packed for re-shipment.

The object of my invention is to provide means for preventing movement of the hoop longitudinally of the barrel and which may be readily removed from the hoop in order that the latter may be removed from the barrel without destroying the hoop or the fastening means.

A further object is to provide means whereby hoops may be reduced in circumference to take out slack without cutting the hoop.

These and further objects will more fully appear in the following specification, and accompanying drawings considered together or separately.

In order that my invention may be better understood attention is directed to the accompanying drawings in which one embodiment of the invention is illustrated, in which like parts in all of the several figures are designated by similar characters of reference and in which—

Figure 1 is a longitudinal sectional view of a portion of metallic, knock-down barrel.

Figure 2 is a side elevation of a portion of a bilge hoop showing the means for securing a hoop to a barrel.

Figure 3 is a section on the line 3—3 of Figure 2.

Figure 4 is a view similar to Figure 2 but showing the means for securing the ends of a hoop together.

Figure 5 is a section on the line 5—5 of Figure 4.

Figure 6 is a detail side elevation showing the ends of a hoop after its circumference has been reduced, and

Fig. 7 is a detail section view of a modification.

In the embodiment of the invention illustrated I have shown a metallic knock-down barrel comprising two staves 1 and 2 ap-

proximately semi-cylindrical in shape. The staves are shown as held in position by means of an end hoop 3, which also secures the head 4 in position, and a bilge hoop 5. It will be understood that each end of the barrel is provided with a hoop 3 and the desired number of bilge hoops 5 may be employed.

Near each end of the staves and at the points where the bilge hoops are to be placed a circumferential, semi-cylindrical recess or groove 6 is rolled in each stave 1 and 2. The recesses or grooves in the staves are oppositely disposed so that when the staves are in position each recess will be continuous around the barrel.

The end hoops are each formed of a single sheet metal member formed to the shape desired and having its ends secured together by a lap joint 7. The bilge hoops are composed of sheet metal bent to circular form with their ends fastened by a lap joint 8.

Each hoop 3, 5 is provided with a series of slots 9 arranged in pairs. The pairs of slots are equally spaced around the hoops. That portion of each hoop between the slots 9 of each pair is bulged outward as at 10 so as to form at each of these points, in conjunction with the groove or recess 6, a cylindrical, open-ended socket 11.

When the hoops are in position with the bulges 10 in alignment with the grooves 6, a key 12 is driven into each socket 11. This key is preferably made of a section of wire cut to a length slightly greater than the length of the socket 11. The diameter of the key is such that it will have a driving fit in the socket. The key may be of relatively soft material such as machinery steel and when driven into the socket it will conform to the curvature of the stave. The driving fit may be relied upon to retain the key within the socket or the ends of the key may be upset as by being nicked with a cold chisel or center-punch in order that a burr 13 may be raised on each end of the key to prevent its removal from the socket. The slot 9 at each side of the bulge 10 permits the key being inserted in the socket and also permits access to the ends of the key so that it may be driven out of the socket.

When the keys are in position the hoops are firmly secured against movement in any direction and particularly against movement in the direction lengthwise of the barrel.

When it is desired to take the barrel apart

for re-shipment the burr 13, at one end of each key is knocked off by means of a cold chisel or is flattened out with a hammer. A center punch is then applied to that end of the key and the key is driven out of the socket by blows of the hammer. When all of the keys in each hoop have been removed the hoop will be released from engagement with the staves and may be removed over the end of the barrel.

After a barrel has been knocked-down and returned to the shipper and the barrel is to be re-formed it may be found that the hoops have been stretched so that they are of greater diameter than the parts of the barrel they are intended to fit.

As this situation would mean that the re-formed barrel would be slack and not suitable for the transportation of fluids, means must be provided for taking up the hoops that the diameters may be reduced.

This is made possible by means of my improved lap joint. The underlying portion 14 of the lap joint has rigidly secured thereto near its extremity a rivet 15. This rivet projects through a slot 16 in the overlapping portion 14^a of the joint and is headed up on the outside of the hoop. Near its extremity the overlapping portion of the joint has rigidly secured thereto a rivet 17 which projects into a slot 18 in the underlying portion 14 of the joint. The slot 18 is counter cut so that the head 19 of the rivet 17 will be flush with the inner surface of the hoop.

When the hoop is manufactured the rivets 15 and 17 will be as close together as the limits of the slots 16 and 18 will permit and the hoop will be of such diameter that a driving operation will be necessary to force it to its position over its proper groove 6 on the staves. If, after knocking-down and when the barrel is to be reassembled it be found that a hoop is too large to have the necessary driving fit with the outside of the barrel a thin wedge 20 may be inserted between the overlapping portions and driven in between the rivets. This will force the rivet 15 to the right in Figure 5 and the rivet 17 to the left. This operation will move the portion 14 of the overlap to the right and the portion 14^a to the left and the circumference of the hoop will be reduced by the sum of the distances the rivets have been moved.

If desirable the groove or recess 6 need not extend entirely around the barrel but may be interrupted and the number of recesses made to correspond to the number and positions of the bulged portions 10.

It may be found advantageous in some situations to reverse the positions of the groove and bulged portion, that is roll the groove in the hoop and the bulges in the staves. In either case the keys must be driven home on the outside of the staves.

Instead of forming a croze on the staves,

as illustrated in Fig. 1, for securing the head 4 in position, a head 21 having a cylindrical extension 22 and a peripheral flange 23 may be employed. The staves may be provided with flanges 24 forming a ledge extending entirely around the end of the barrel. A gasket 25 is positioned between the flanges 23 and 24 to make a fluid tight joint. The head hoop is applied and secured in position in the same manner as is shown in Fig. 1.

In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having now described my invention what I claim and desire to secure by Letters Patent, is:

1. A barrel having a groove or depression therein, a hoop encircling the barrel and covering the groove or depression, a groove or depression in the hoop, said grooves or depressions being oppositely disposed, and removable means engaging the grooves or depressions whereby the hoop will be secured against movement longitudinally of the barrel.

2. A barrel having a groove or depression therein, a hoop encircling the barrel and covering the groove or depression, a groove or depression in the hoop, said grooves or depressions being oppositely disposed, and a relatively short key engaging the grooves or depressions whereby the hoop will be secured against movement longitudinally of the barrel.

3. A barrel having an endless groove or depression therein, a hoop encircling the barrel and covering the groove or depression, a groove or depression in the hoop, said hoop groove being of less length than the barrel groove, said grooves or depressions being oppositely disposed, and means engaging the grooves or depressions whereby the hoop will be secured against movement longitudinally of the barrel.

4. A barrel having an endless, circumferential groove or depression therein, a hoop encircling the barrel and covering the groove or depression, a groove or depression in the hoop, said hoop groove being of less length than the barrel groove, said grooves or depressions being oppositely disposed, and a removable key engaging the grooves or depressions whereby the hoop will be secured against movement longitudinally of the barrel.

5. A barrel having a circumferential groove or depression therein, a hoop encircling the barrel and covering the groove or depression, said hoop having a bulged

- portion in line with but oppositely disposed to the groove so as to form a socket between the groove and bulged portion, and a key within the socket, there being an opening in the hoop to permit entrance and egress of the key. 5
6. A barrel having a circumferential groove or depression therein, a hoop encircling the barrel and covering the groove or 10 depression, said hoop having a bulged portion in line with but oppositely disposed to the groove so as to form a socket between the groove and bulged portion, a key within the socket, and means for preventing removal of the key. 15
7. A barrel having a circumferential groove or depression therein, a hoop encircling the barrel and covering the groove or depression, said hoop having a bulged portion in line with but oppositely disposed to the groove so as to form a socket between the groove and bulged portion, a key within the socket, and means at opposite ends of the key for preventing removal of the key. 20
25. 8. A barrel having an endless, circumferential groove therein, a hoop encircling the barrel and covering the groove, said hoop having a plurality of aligned bulged portions in line with but oppositely disposed relatively to the barrel groove whereby a 30 socket is formed between each bulged portion of the hoop and the barrel groove, there being an opening at each end of each
- hoop bulge, a short key disposed within each socket and means for preventing removal of the keys. 35
9. A hoop having overlapping portions, means secured to each portion to prevent lateral separation of the portions, there being a slot in each portion, the fastening means secured to one portion engaging the slot in the other portion, and means for separating the securing means whereby the circumference of the hoop will be reduced. 40
10. A metallic barrel having a circumferential depression therein, a hoop encircling the barrel and covering the groove formed by the depression, the material of the hoop being depressed at intervals to form a plurality of separated pockets, said pockets being in alignment with the groove of the barrel and in opposition thereto, said pockets occupying a short portion of the periphery of the hoop, an end of each pocket being open, and a key adapted to be inserted in the opening to engage each pocket and the groove to prevent longitudinal movement of the hoop relatively to the barrel, and means for securing the keys in the pockets. 45
